UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

HINGED CURTAIN-SHIELD.

1,256,047.

Specification of Letters Patent. Patented Feb. 12, 1918.

Application filed August 15, 1914. Serial No. 856,933.

To all whom it may concern:

Be it known that I, HARRY H. SCHROYER, a citizen of the United States, and a resident of the city of Chicago, in the county 5 of Cook and State of Illinois, have invented certain new and useful Improvements in Hinged Curtain-Shields; and I do hereby declare that the following is a full, clear, and exact description of the same, reference being had to the accompanying drawings, and to the numerals of reference marked thereon, which form a part of this specification.

This invention relates to that type of 15 shield and mounting means particularly well adapted for use with car window curtains set forth in my co-pending application for "Revolving curtain shields", executed and filed of even date herewith.

20 However, in the present construction although the curtain roller is mounted within, and is bodily movable with the curtain shield, the shield is pivotally or hingedly attached to the window frame in a manner 25 to permit the shield swinging inwardly away from the frame, and upwardly to afford access to the curtain roller.

It is an object of this invention to construct a hingedly mounted support and 30 shield for a curtain roller, which, when swung away from the window frame, affords ready access to the curtain roller and when in closed position conceals and protects the roller, so that unauthorized interference therewith is prevented.

It is also an object of this invention to construct a semi-cylindrical shield or casing for a curtain roller, acting to support the roller rotatably therein, and hingedly mounted 40 upon the window frame of a car, so that the associated curtain roller and shield may be swung inwardly away from the window frame for purposes of repair or adjustment of the curtain.

45 It is also an object of this invention to construct a hingedly mounted curtain shield and support for a spring roller so constructed that the hinged connection thereof to the window frame is entirely concealed, so that 50 to one unacquainted with the structure, the means of opening the same is not readily apparent.

It is furthermore an important object of

this invention to construct a support and shielding means for a curtain roller adapted to protect and conceal the same from view, and preventing detachment of the roller when in closed position, but when in open position releasing the roller for removal, and with spring actuated locking 60 mechanisms to retain the shield in closed position.

It is finally an object of this invention to construct a mechanism cheap to manufacture and simple in operation, and acting effectually to shield and conceal a curtain in position upon a car window in a manner permitting ready access thereto, and affording on the whole a very neat and compact device.

The invention (in a preferred form) is illustrated in the drawings and hereinafter more fully described.

In the drawings:

Figure 1 is a front elevation of a car window illustrating a curtain mechanism embodying the principles of my invention mounted thereon.

Fig. 2 is a section taken on line 2—2 of Fig. 1, with parts shown in elevation.

Fig. 3 is an enlarged front face view of the device connected on a window.

Fig. 4 is a detail section with parts in elevation taken on line 4—4 of Fig. 3.

Fig. 5 is a fragmentary section taken on line 5—5 of Fig. 3, with the operation illustrated in dotted lines.

Fig. 6 is an enlarged fragmentary section taken on line 6—6, of Fig. 3, with parts in elevation and with parts omitted.

As shown in the drawings:

The curtain roller is indicated by the reference numeral 1, and has wound thereon a curtain 2, the lower edge of which is provided with an enlarged tubular portion 3, through which extends a curtain stop of any suitable or conventional construction, the ends of the stop engaging in guides 4, secured upon window posts 5, of a window frame. In the car window frame herein illustrated an inner sash 6, and an outer sash 7, are provided, which slide upwardly in the window frame in suitable guides between an inner transom light 8, and an outer transom light 9. Secured transversely between the window posts 5, near the lower

end of the inner transom light 8, is a transverse channel member 10, which, at its ends, is secured to face plates 11, which are in turn securely mounted upon the respective window frame posts.

A shielding support for said curtain roller 1, is hingedly connected to said transverse member 10, and comprises a semi-cylindrical casing 12, which, along its upper edge on the inner surface thereof, is connected by means of hinges 13, to the lower flanges of said channel member 10, and along its lower edge is provided with a rectangular bead 14, which extends horizontally between the window posts and plates 11, thereon, when the shield is in closed position. A pair of circular end plates 15, having an inturned flange 16, extending along a part of the periphery thereof, are rigidly secured thereby to said shield member 12, and attached upon the inner surface on each of said end plates 15, are supporting members 17 and 17^a, to receive the squared and rounded gudgeon ends of the curtain roller 1, therein, the member 17, having a rectangular recess for the squared gudgeon and the member 17^a, a round recess for the other roller gudgeon. An open guide way or slot communicates in said squared recess of the member 17, and is directed rearwardly and slightly upwardly with the shield in normal or closed position shown in Fig. 5.

Rounded end caps 18, are integrally formed upon the plates 11, and are each provided with an ornamental rib 19, and secured within each of said caps and parallel to the movable end plates 15, of the curtain shield, are semi-circular reinforcing plates 20, each provided with an inwardly directed flange 21, secured within and beneath the rib 19, of said rounded cap members. As clearly shown in Fig. 4, the semi-cylindrical shell or casing 12, extends slightly beyond the end plates 15, to fit closely to the ends of the cap members 18, when the shield is in closed position, bearing upon the flange 21, of the inner reinforcing plate 20. Small spring impelled locking bolts or detents 22, are mounted within the tubular rectangular bead 14, at each end of the curtain shield, and each engages behind one of the plates 11, in a suitable recess provided therefor to hold the shield in closed position.

The operation is as follows:

In order to gain access to the curtain roller to either detach or repair the same, or for any other reason, the operator merely pulls outwardly upon the lower beaded edge 14, of the curtain shield, thereby springing the detents 22, inwardly and permitting the shield 12, to be swung upwardly into the position shown in dotted lines in Fig. 5. Inasmuch as the circular end plates 15, which support the ends of the curtain roller 1, are rigidly attached to and form a part of the

curtain shield, and move therewith when the same is swung away from the window frame, the curtain roller likewise moves therewith, and it is readily apparent that the utmost ease of access thereto is thus afforded. Then, too, said end plates 15, act to guide the curtain shield in its various positions of adjustment, inasmuch as the same lie closely adjacent to the reinforcing plates 20, beneath the rounded end members 18. The meeting point between the curtain shield 12, and the end members 18, is at the base of the bead or rib 19, formed on the rounded end member, so that said meeting edge is not readily visible, and the whole device appears as a unitary construction, and is therefore of very neat appearance.

The curtain roller is positively retained in the shield member when the same is in closed position, due to the fact that the entrance slot or passage for the squared gudgeon end thereof in the member 17, is directed rearwardly and upwardly, but when the shield is swung inwardly into open position, said slot is then directed downwardly, permitting easy detachment and removal of the curtain roller.

I am aware that various details of construction may be varied through a wide range without departing from the principles of this invention, and I therefore do not purpose limiting the patent granted otherwise than necessitated by the prior art.

I claim as my invention:

1. In a device of the class described, the combination with a window frame and a transverse horizontal member secured thereon, of a semi-cylindrical curtain shield hinged along one of its edges to said transverse member near each end thereof, a hollow bead integral with the lower edge of the shield, a locking bolt therein adapted to automatically lock and release the shield by actuating the shield, a stationary member secured upon the window frame of each side thereof beneath said transverse member adapted to limit the closing movement of the shield into closed position, and a curtain roller journaled within said shield and movable therewith.

2. In a device of the class described, face plates, reinforcing plates secured thereto projecting outwardly therefrom, a curtain shield bearing at the ends on said reinforcing plates, end plates in the shield spaced inwardly from the ends and a curtain in the shield.

3. In a device of the class described, face plates, reinforcing plates secured thereto projecting outwardly therefrom, a curtain shield bearing at the ends on said reinforcing plates, end plates in the shield spaced inwardly from the ends, a curtain in the shield and a member carried by the shield

adapted to frictionally lock the shield in closed position and adapted to automatically release the shield by pulling on the shield.

4. In a device of the class described, the combination with a window frame, of a curtain shield hingedly connected to the frame, a curtain roller mounted within said shield and movable therewith, and curtain guides secured upon the window frame with one edge of the shield in alinement therewith when in closed position, said guides adapted to guide the curtain as the same is extended and unwound from the roller with the shield in closed position.

5. In a device of the class described, end caps provided with beads, plates secured to the end caps provided with bearing flanges, a curtain shield having its ends bearing on the flanges and fitting closely to the beads and a curtain carried by the shield.

6. In a device of the class described, a rotatable curtain shield hinged to a window frame, a curtain therein, face plates, means on the face plates interfitting the shield to guide the same in rotating and a spring

pressed locking member carried by the shield.

7. In a device of the class described, the combination with a window frame, of a transverse member secured thereacross, a curved curtain shield hinged along one edge thereof at the ends of said transverse member adapted to swing upwardly with respect thereto, stationary end caps secured on the window frame beneath said transverse member, curved projecting flanges on said end caps on which the ends of said curved shield is adapted to bear when in normal position, means in the interior of said curved shield for supporting a curtain roller therein, and mechanisms for positively locking the curved shield in closed position on the window frame.

In testimony whereof I have hereunto subscribed my name in the presence of two subscribing witnesses.

HARRY H. SCHROYER.
